SEAT AND DESK COMBINATION

Chester J. Barecki, Grand Rapids, and Carl W. Sundberg and Montgomery Ferar, Southfield, Mich., assignors to American Seating Company, Grand Rapids, Mich., a corporation of Delaware

Filed Dec. 2, 1966, Ser. No. 4,896

Term of patent 14 years

(Cl. D33—11)

FIGURE 1 is a perspective view of a seat and desk combination showing our new design; and

FIGURE 2 is a perspective view of the same, the view being taken from the rear of the chair.

The design is characterized by the rear of the backrest wherein the square opening at the center thereof is formed with a rearwardly extending rim and member in combination with the tubular frame support for the back which extends upwardly against the transverse rim thereby to enclose the square rim, all as shown in FIG. 2.

We claim:

The ornamental design for a seat and desk combination, as shown and described.
